United States Patent [19]

Sakaki et al.

[11] Patent Number: Des. 307,435

[45] Date of Patent: ** Apr. 24, 1990

[54] AUTOMATIC STRAPPING MACHINE

[75] Inventors: Yasunori Sakaki, Tokyo; Tsutomu Tagomori, Yokohama, both of Japan

[73] Assignee: Strapack Corporation, Tokyo, Japan

[**] Term: 14 Years

[21] Appl. No.: 122,430

[22] Filed: Nov. 19, 1987

[30] Foreign Application Priority Data

May 27, 1987 [JP] Japan 62-20658

[57] CLAIM

The ornamental design for an automatic strapping machine, as shown and described.

DESCRIPTION

FIG. 1 is a front perspective view of an automatic strapping machine showing our new design;

FIG. 2 is a front elevational view;

FIG. 3 is a rear elevational view;

FIG. 4 is a top plan view;

FIG. 5 is a left-side elevational view;

FIG. 6 is a right-side elevational view; and

FIG. 7 is a bottom plan view thereof.

The strapping material shown in broken lines in FIG. 1 is for illustrative purposes only and forms no part of the claimed invention.
